UNITED STATES PATENT OFFICE.

HARRY C. BREWSTER, CHARLES A. DUTHERAGE, AND WALTER L. GLIDDEN, OF SHREVEPORT, LOUISIANA.

RAILWAY-RAIL JOINT.

No. 808,509.

Specification of Letters Patent.

Patented Dec. 26, 1905.

Application filed April 20, 1905. Serial No. 256,585.

To all whom it may concern:

Be it known that we, HARRY C. BREWSTER, CHARLES A. DUTHERAGE, and WALTER L. GLIDDEN, citizens of the United States, and 5 residents of Shreveport, in the parish of Caddo and State of Louisiana, have made certain new and useful Improvements in Railway-Rail Joints, of which the following is a specification.

Our invention is an improved means for connecting and supporting the meeting ends of railway-rails. It is more particularly an improvement in forms of truss connections and braces in which slideable wedges are employed to enable the parts to be readily tightened in order to preserve a rigid or unyielding support for the rails.

The details of construction, arrangement, and combination of parts are as hereinafter described and claimed, and illustrated in the accompanying drawings, in which—

Figure 1 is a side view illustrating our improved rail-joint. Fig. 2 is a longitudinal section of the same on the line 2 2, of Fig. 3. 25 Fig. 3 is a vertical cross-section on the line 3 3 of Fig. 1. Fig. 4 is a perspective view of the two wedges forming part of the rail-joint. Fig. 5 is a perspective view of the base-plate upon which the rail end runs.

The alined rails A A are constructed in the usual manner.

B B (see especially Fig. 3) indicate two fish-plates, which are secured to the rail ends A by bolts C in the usual manner. These fish-35 plates proper have lateral and downward extensions or flanges B', whose lower edges are provided with holes to receive a series of cross-bolts D.

The rail ends A rest and are supported upon 40 a base-plate E, whose end portions are enlarged or extended laterally, as shown in Fig. 5, and provided with notches e to receive spikes F, that fasten them to the sleepers G, as shown in Fig. 1. This fastening is necessary 45 in order to prevent the rails moving or creeping, especially on an incline. As will be understood from the drawings, the extensions or flanges B' of the fish-plates fit between the shoulders e' of the base-plate E, so that the base-plate and rail ends are prevented from moving on each other save to a very limited extent.

Between the base-plate E and the cross-bolts D, which connect the lower edges of the

flanges B', are arranged two wedges H and 55 H'. The upper wedge H' is provided with two transverse grooves h, which receive shoulders e', (see Fig. 2,) whose function is to prevent movement of the wedge longitudinally of the base-plate E. The lower wedge 60 H has a series of transverse grooves h² to receive the cross-bolts D, as will be readily understood by inspection of Fig. 2. As indicated by dotted lines in Fig. 3, the pendent flanges B' of the fish-plates diverge laterally 65 to a slight degree instead of being parallel, but they are drawn toward each other, and thus reach or approximate a parallel position by tightening the nuts of the bolts D. It is apparent that the same operation forces 70 the wedges H H' laterally in such way that they slide or ride on each other, and thus tend to force the base-plate E and rail ends A upward, or, in other words, to tighten the parts composing the entire rail-joint.

75

It will be seen from the construction, arrangement, and combination of parts described we provide a very strong and rigid connection and brace or truss for the meeting ends of the rails, and one which may be 80 quickly and easily adjusted whenever it is required to tighten the connection still further.

We make provision for bonding the rail ends A electrically as occasion may require. To this end we provide the base-plate E (see 85 Fig. 5) with a longitudinal groove e² in its upper side, the same having its ends considerably enlarged, as shown. A copper or other wire I (see Fig. 2) is laid in this groove e² and its ends project up through the holes in the base 90 of the rail ends A. The enlarged ends of the groove e² will allow slight shifting or end-wise movement of the rail ends without any danger of the wire I being cut or otherwise injured.

95

Having thus described our invention, what we claim as new, and desire to secure by Letters Patent, is—

1. The combination, with alined rail ends, of fish-plates having lateral and downwardly-extended flanges, cross-bolts connecting the fish-plates and rails, and other bolts connecting the lower edges of their flanges, a base-plate and wedges arranged between the rail-bases and the lower row of cross-bolts, substantially as described.

100

2. The combination, with alined rail ends, of fish-plates which are secured to the ends of

105

the rail, and having lateral and downward extensions, transverse bolts connecting the lower edges of said flanges, and the latter diverging laterally from vertical planes, and 5 wedges interposed between the said bolts and the bases of the rails, substantially as described, whereby, upon tightening the nuts on the said bolts the wedges are caused to slide upon each other to a corresponding degree, substantially as described.

3. The combination, with alined rail ends and ties supporting the same and spaced apart, of fish-plates having lateral and downwardly-extending flanges, a base - plate arranged beneath the ends of the rails and having its enlarged ends secured to the ties, cross-bolts connecting the lower edges of the flanges and wedges interposed between the bolts and base-plate, substantially as described.

20 4. The combination, with alined rail ends and ties upon which the same rest, of a base-plate which is spiked to the ties and having a body portion of less width than its ends, fish-plates having flanges extending downward in the space between the heads of the base-plate, transverse bolts securing the lower edges of the flanges, and wedges interposed 25 between the said bolts and the base-plate, substantially as described.

5. The combination, with alined rail ends, 30 and fish - plates extending downward, and having other pendent portions connected by cross - bolts, of wedges interposed between said base - plate and cross - bolts, the lower wedge having a series of transverse grooves 35 to receive the said bolts, substantially as described.

6. The combination, with alined rail ends, of fish-plates having lateral and downwardly-extended flanges which diverge laterally, 40 cross-bolts connecting such divergent portions, and means arranged between the rail ends and the cross - bolts, which serve, when the ends of the cross - bolts are tightened, to apply pressure upwardly and downwardly 45 upon the rail ends, substantially as described.
